CLAIM

The ornamental design for a magnetically held household display and storage device for menus, recipes, notes and the like, as shown and described.

DESCRIPTION

FIG. 1 is a perspective view of a magnetically held household display and storage device for menus, recipes, notes and the like showing my new design, with the broken line disclosure of menu cards, recipe cards and note paper being for illustrative purposes only and forming no part of the claimed design;

FIG. 2 is a front elevational view thereof;

FIG. 3 is a rear elevational view thereof;

FIG. 4 is a top view thereof;

FIG. 5 is a bottom view thereof;

FIG. 6 is a left side elevational view thereof;

FIG. 7 is a right side elevational view thereof;

FIG. 8 is a cross sectional view thereof, taken along line 8—8 of FIG. 1;

FIG. 9 is a cross sectional view thereof, taken along line 9—9 of FIG. 1; and,

FIG. 10 is a cross sectional view thereof, taken along lines 10—10 of FIG. 1.
